(57) **CLAIM**

The ornamental design for a folding wagon, as shown and described.

DESCRIPTION

FIG. 1 is a perspective view of a folding wagon, showing my new design;

FIG. 2 is another perspective view thereof;

FIG. 3 is a rear elevation view thereof;

FIG. 4 is a front elevation view thereof;

FIG. 5 is a right elevation view thereof;

FIG. 6 is a left side elevation view thereof;

FIG. 7 is a top plan view thereof;

FIG. 8 is a bottom plan view thereof; and,

FIG. 9 is a partially enlarged view of an area labeled 9 in FIG. 1.

The broken lines shown in the figures illustrate portions of the folding wagon that form no part of the claimed design. The dot-dash-dot broken lines depict boundaries of the detailed enlargement that form no part of the claimed design.
